SYSTEM FOR ELIMINATING RADIO
INTERFERENCE

Josef Friedrich Heuberger, Stockholm, Sweden,
assignor to Electrolux Corporation, Dover, Del.,
a corporation of Delaware

Application February 23, 1933, Serial No. 658,032
In Germany March 7, 1932

9 Claims. (Cl. 171—97)

This invention relates to a system for eliminating radio interference and more particularly to a system for preventing the propagation of high frequency disturbances by dynamo electric machines.

One object of the invention is to prevent electric motors of household appliances from interfering with radio reception.

Another object is to provide a protective means for portable household appliances such as vacuum cleaners, floor polishers, and the like.

A further object is to provide a simple, safe and convenient device for the above purpose.

The invention also consists in certain new and original features of construction and combinations of parts hereinafter set forth and claimed.

Although the novel features believed to be characteristic of this invention will be particularly pointed out in the claims appended hereto, the invention itself, as to its objects and advantages, and the manner in which it may be carried out, may be better understood by referring to certain preferred embodiments thereof which are shown in the accompanying drawing for purposes of illustration only.

Of the drawing:

Fig. 1 is a diagrammatic representation of one embodiment of the invention, and

Figs. 2 to 7 inclusive are diagrammatic representations illustrating various modifications thereof.

Like reference characters denote like parts in the various figures.

In the following description and in the claims various details will be identified by specific names for convenience but they are intended to be as generic in their application as the state of the art will permit.

Referring to the drawing, 10 designates a housing which may consist of, for example, the housing of a household appliance such as a vacuum cleaner, floor polisher or the like. Located within this housing and electrically insulated therefrom is an electric motor having an armature 11, brushes 12 and field coils 13 which are shown, by way of example, as connected in series relationship. The motor is connected to a line 15 by which current is supplied thereto. A suitable switch 25 may be included for controlling the operation of the motor.

An impedance, such as a pair of condensers 14, is connected across the brushes 12 of the motor and is enclosed in a metallic casing 17 which is adapted to provide an electrostatic shield.

55 A second impedance, such as a condenser 16, is connected across the line 15 and across the field coils 13. This condenser 16 is also enclosed in a suitable metallic casing 18 similar to the casing 17. It is to be understood that casings 17 and 18 may be insulated from each other and

are insulated from the housing 10. For convenience, the condensers 14 which are connected across the brushes 12 will be hereinafter designated as brush condensers whereas the condenser 16 which is connected across the line 15 will be designated as the field or line condenser. 5

The condensers 14 and 16 are connected to casings 17 and 18 in various ways, as will be hereinafter described, either directly or through protective condensers, to form a protective circuit 10 which is adapted to constitute a high frequency by-pass, or a high frequency filter to prevent high frequency disturbances due, for example, to improper commutation or sparking at the brushes, from being transmitted to the line or to the exterior, and thereby interfering with radio reception. 15

In the form of the invention illustrated in Figure 1, the condensers 14 are connected in series and the midpoint thereof is connected to the 20 housing 18 of the line condenser 16.

Referring to the modifications of the invention illustrated in the other figures, Fig. 2 shows the mid-point of the brush condenser 14 connected to the casing 17 which surrounds said condenser. In Figure 3 the casings 17 and 18 are interconnected and the brush condenser 14 is connected to the casing 17. In Fig. 4, the casing 18 is grounded externally of housing 10 through a protective condenser 19 and the brush condenser 30 25 14 is connected to said casing 18.

In the form illustrated in Figure 5, the brush condenser 14 is connected to the casing 18 through a protective condenser 28 and the line condenser 16 is formed in two sections which are 35 interconnected, the mid-point being connected to the casing 17 through a protective condenser 29.

In Figure 6, the casings 17 and 18 are interconnected, the brush condenser 14 is connected to the casing 17 through a protective condenser 40 30 and the line condenser 16 is connected to the casing 18 through a protective condenser 31.

In the form of the invention illustrated in Figure 7, condensers 14 and 16 are both enclosed in a single metallic casing 20 to which the condenser 14 is connected through a protective condenser 21. 45

In the form of the invention illustrated in Figs. 4-7, it is to be understood that one or more of the protective condensers 19, 21 and 28 to 31 may 50 be omitted and one or more of the casing connections in Figs. 5 and 6 may be omitted in instances where the disturbance is eliminated satisfactorily by the remaining connections as will be apparent to a person skilled in the art. Specific embodiments have been disclosed for purposes of illustration only. In any event the casings 17 and 18 constitute electrostatic shields and the various condensers together with the casings 55 60

17 and 18, provide filter means for the purpose above specified.

It is to be noted that the housing 10 is electrically insulated from all parts of the motor circuit and that the protective condensers are grounded to separate casings which in themselves are electrically insulated from the housing 10. This arrangement eliminates the danger of the operator coming in contact with the charged part of the apparatus and receiving an electrical shock therefrom. The embodiments of Figs. 1-3 and 5-7 also eliminate the necessity for a third wire connecting the apparatus to ground. This latter feature is of importance in connection with portable apparatus of the type above specified which would otherwise require a three wire cable and would require a special type of wall socket for grounding purposes.

The filter circuit may be installed as a unit, no part of which extends without the main housing and no part of which is exposed to accidental contact. Furthermore the device has been found particularly efficacious for the purpose specified.

While certain embodiments of the invention have been disclosed for purposes of illustration, it is to be understood that the invention is only to be limited in accordance with the following claims when interpreted in view of the prior art.

What I claim is:

30 1. In combination with an electric motor adapted to form a part of a utility and having a commutating means and brushes associated therewith, a housing surrounding said motor and electrically insulated therefrom, means for preventing propagation of electrical disturbances comprising condenser means electrically interconnecting said brushes, and a metallic casing surrounding said condenser means, said casing being located within said housing and insulated therefrom, said condenser means being grounded to said casing.

45 2. In combination with an electric motor adapted to form a part of a utility and having commutating means, brushes, field windings and a current supply line, a housing surrounding said motor and electrically insulated therefrom, means for preventing propagation of electrical disturbances comprising condenser means electrically connected across said line, and a metallic casing surrounding said condenser means, said casing being located within said housing and insulated therefrom, said condenser means being grounded to said casing.

55 3. In combination with an electric motor adapted to form a part of a utility and having commutating means, brushes, field windings and a current supply line, a housing surrounding said motor and electrically insulated therefrom, means for preventing propagation of electrical disturbances comprising a condenser electrically interconnecting said brushes, a second condenser connected across said line and a separate casing surrounding each of said condensers and insulated from said housing, said condensers being grounded to said casings.

60 4. In combination with an electric motor adapted to form a part of a utility and having commutating means, brushes, field windings and a current supply line, a housing surrounding said motor and electrically insulated therefrom, means for preventing propagation of electrical disturbances comprising a condenser electrically interconnecting said brushes, a second condenser connected across said line and a separate casing 65 surrounding each of said condensers and insu-

lated from said housing, one of said condensers being grounded to one of said casings through a protective condenser.

5 5. In combination with an electric motor adapted to form a part of a utility and having commutating means, brushes, field windings and a current supply line, a housing surrounding said motor and electrically insulated therefrom, means for preventing propagation of electrical disturbances comprising a condenser electrically interconnecting said brushes, a second condenser connected across said line and a separate casing surrounding each of said condensers and insulated from said housing, said first condenser being connected to its casing.

10 6. In combination, a housing adapted to form a part of a utility, an electric motor mounted within said housing, said motor having a commutator, brushes and field windings and current supply connections, said motor being electrically insulated from said housing, a pair of condensers, a separate metallic casing enclosing each of said condensers, each casing being electrically insulated from said housing, one of said condensers being connected across the brushes of said motor, the other of said condensers being connected across said current supply connections and means grounding one of said condensers to one of said casings.

15 7. In combination, a housing adapted to form a part of a utility, an electric motor mounted within said housing, said motor having a commutator, brushes, field windings and current supply connections, said motor being electrically insulated from said housing, a pair of condensers, a separate metallic casing enclosing each of said condensers, each casing being electrically insulated from said housing, one of said condensers being connected across the brushes of said motor, the other of said condensers being connected across said current supply connections and means grounding one of said condensers to one of said casings, and means grounding said last casing externally of said housing.

20 8. In combination, a housing adapted to form a part of a utility, an electric motor mounted within said housing, said motor having a commutator, brushes, field windings and current supply connections, said motor being electrically insulated from said housing, a pair of condensers, a separate metallic casing enclosing each of said condensers, each casing being electrically insulated from said housing, one of said condensers being connected across the brushes of said motor, the other of said condensers being connected across said current supply connections and means grounding one of said condensers to one of said casings and means grounding said last casing externally of said housing, said last means including a protective condenser.

25 9. In combination, a housing adapted to form a part of a utility, an electric motor mounted within said housing, said motor having a commutator, brushes associated therewith, field windings and current supply connections, said motor being electrically insulated from said housing, a pair of condensers, a metallic casing enclosing said condensers, said casing being electrically insulated from said housing, one of said condensers being connected across the brushes of said motor, the other of said condensers being connected across said current supply connections and means grounding one of said condensers to said casing.
